(57) CLAIM

The ornamental design for a coffee cup sleeve, as shown and described.

DESCRIPTION

FIG. 1 is a top-perspective view of a coffee cup sleeve, showing my new design;

FIG. 2 is a top perspective view thereof, shown in a position of use with an exemplary coffee cup;

FIG. 3 is a front view thereof;

FIG. 4 is a side view thereof;

FIG. 5 is a front view thereof, shown in a position of use with additional exemplary environment; and,

FIG. 6 is a front view thereof, shown with the exemplary coffee cup removed to show aspects of the design not visible when combined.

The broken lines are shown for the purpose of illustrating both parts of the article as well as exemplary environmental subject matter. None of the broken lines form part of the claimed design.
